UNITED STATES PATENT OFFICE.

JOHN P. RYDER, OF KANSAS CITY, MISSOURI.

GAS GUARD AND LUBRICATOR FOR STEAM ENGINES.

Application filed December 13, 1920. Serial No. 430,368.

To all whom it may concern:

Be it known that I, JOHN P. RYDER, a citizen of the United States, residing at Kansas City, in the county of Jackson and State of Missouri, have invented a certain new and useful Improvement in Gas Guards and Lubricators for Steam Engines, of which the following is a specification.

My invention relates to improvements in 10 gas guards and lubricators for steam engines.

One of the objects of my invention is to provide novel means for carrying a lubricating fluid, such as wet steam, through the 15 exhaust conductor or conductors into the steam chest or chests, whereby the steam chests and cylinders are lubricated when the steam is shut off in the ordinary manner.

A further object of my invention is to 20 provide novel means for increasing the draft through the smoke stack and also excluding gas, fine ashes and carbonaceous material from passing from the smoke box into the exhaust conductor, thus avoiding carbonization 25 and the clogging up of the exhaust pipes, steam chests and cylinders due to the sucking into the cylinders of such deleterious substances from the smoke box through the exhaust pipes.

My invention is particularly well adapted 30 for use on locomotives, and is of particular value for locomotives that employ superheated steam.

A further object of my invention is to 35 provide a novel device of the kind described, which is cheap to make, durable and not liable to get out of order, which is efficient in operation, and which can be readily and economically applied to engines now in use.

The novel features of my invention are 40 hereinafter fully described and claimed.

In the accompanying drawing, which 45 illustrates the preferred embodiment of my invention as applied to a locomotive of a usual type,

Fig. 1 is a vertical cross section through the smoke box of a locomotive which is provided with my improvement, some of the parts being broken away.

Fig. 2 is an enlarged vertical sectional view of the two annular tubular members and some of the parts connected therewith.

Fig. 3 is a top view of the upper annular tubular member.

Fig. 4 is a top view of the lower annular tubular member.

Similar reference characters designate similar parts in the different views.

1 designates the cab, 2 the boiler, 3 the smoke box, 4 the smoke stack, 5 the petticoat, 6 the steam chests, 7 the cylinders, 8 the nozzle located in the smoke box 3 and discharging through the petticoat 5 into the smoke stack 4, and 9 the exhaust pipes respectively connected to the steam chests 6 65 and discharging into the lower end of the nozzle 8, and forming therewith the exhaust conductor. The parts just described are the usual elements embodied in the modern type of American locomotives. In such locomotives, particularly in those of the superheated steam type there is great liability of the exhaust pipes clogging through the suction thereinto of fine ashes, gas and carbonaceous materials. Furthermore carbon 75 deposits in the steam chests and cylinders also occurs due to the decomposition of the lubricating oil therein, when the steam is shut off.

In order to prevent the burning of the oil 80 in the cylinders and steam chests, when the engine is drifting and the steam is shut off, I provide means for forcing wet steam downwardly through the exhaust conductors into the steam chests and cylinders. In the 85 preferred embodiment of my invention, as shown in the drawing, such means consists in the following described parts.

10 designates an annular tubular member mounted concentrically on the upper end of 90 the nozzle 8, and having one or more inwardly inclined and downwardly inclined outlet openings 11, the latter being arranged so that fluid under pressure in the member 10 will be discharged downwardly through 95 the nozzle 8, and exhaust pipes 9 into the steam chests 6 and cylinders 7. Preferably the fluid employed is steam which is conducted from the boiler 2 by a pipe 12, which passes into the cab 1 and communicates with 100 the annular passage 13 in the member 10, which passage communicates with the outlet openings 11. In the pipe 12 is a shut off valve 14 by which steam from the boiler may be shut off, by the engineer or fireman, 105 from the annular member 10.

When the engineer is about to shut off steam from the cylinders 7 in the usual manner, he first opens the valve 14 and then shuts off the steam with the usual throttle, 110 not shown. The wet steam from the boiler will then pass by the pipe 12 into the mem-

ber 10 and thence through the openings 11 downwardly through the nozzle 8 and pipes 9 through the exhaust passage into the steam chests 6 and cylinders 7. The wet steam will afford sufficient lubrication and will, by its relative coolness, in engines using superheated steam, prevent the burning or vaporization of the oil in the steam chests and cylinders. When the engineer again opens the 10 throttle, he closes the valve 14.

For preventing the suction into the steam chests, exhaust pipes and cylinders of fine ashes, gas and soot from the smoke box, when the engine is drifting or when the engine is running under a head of steam and more draft is desired, I provide means for making a tubular fluid column which discharges into the smoke stack 4 and which encircles the discharge end of the nozzle 8 and through which the nozzle discharges into the smoke stack 4. This tubular fluid column prevents deleterious materials, such as hot gas, soot, and fine ashes being sucked into the cylinders 7, steam chests 6, exhaust pipes 9 and nozzle 8 when the engine is drifting, and at the same time affords means for increasing the draft of the smoke stack.

Such means comprises, preferably the following described parts.

30 15 designates an annular tubular member having an annular passage 16, said member being mounted concentrically upon the member 10, the passage 16 being in communication with a steam pipe 17 having a valve 18 and connected with the boiler 2. The member 15 is provided with suitable means for projecting upwardly a tubular column of steam comprising, preferably, two concentric rows of openings 19 and 20 in the 40 top of the member 15, the openings of one row, preferably, being staggered or overlapping the openings of the other row, thereby forming a tubular steam column which is discharged into the smoke stack 4 through the petticoat pipe 5. The tubular steam column received from the nozzle 8 forms a guard for preventing the engine, when drifting, from sucking hot gas, smoke, soot, ashes or cinders from the smoke box 3 into the nozzle 45 8. Steam is preferably supplied to the annular member 15 through the steam pipe 17, but it may be supplied from any other suitable source, as with the exhaust from the air pump on the engine, the air pump being connected at its exhaust outlet with the passage 16 by a pipe 21, which may be provided with a shut off valve 22. By opening the valve 22 the exhaust steam from the air pump will be discharged into the passage 50 60 16 through the pipe 21. When the pipe

21 is connected to the exhaust of the air pump, the valve 22 may be eliminated, or if present, it should be kept open.

I do not limit my invention to the structure shown and described, as various modifications, within the scope of the appended claims, may be made without departing from the spirit of my invention.

What I claim is,

1. In an apparatus of the kind described, 70 the combination with the boiler, steam chest and exhaust conductor of an engine, of means by which steam from the boiler may be forced through the exhaust conductor toward the steam chest, substantially as set forth.

2. In an apparatus of the kind described, 80 the combination with the steam chest and exhaust conductor connected therewith of an engine, an annular tubular member at the discharge end of said conductor and having means for discharging fluid therefrom through said conductor toward said steam chest, and means for supplying fluid to said annular member, substantially as set forth. 85

3. In an apparatus of the kind described, 90 the combination with the steam chest, exhaust conductor connected therewith and boiler of an engine, of an annular tubular member at the discharge end of said conductor having means for discharging steam therefrom through said conductor toward said steam chest, and means for supplying steam from said boiler to said annular member, substantially as set forth. 95

4. In an apparatus of the kind described, 100 the combination with the steam chest, exhaust conductor connected therewith and boiler of an engine, of an annular tubular member at the discharge end of said conductor and concentric therewith and having one or more outlets arranged to discharge into the conductor toward the steam chest, and a steam pipe connecting the boiler and said annular member, substantially as set forth. 105

5. In an apparatus of the kind described, 110 the combination, in an engine, with a smoke stack, boiler, and exhaust conductor arranged to discharge into the smoke stack, of an annular tubular member concentrically mounted on the upper end of the conductor and having one or more downwardly directed outlets arranged to discharge steam downwardly into the exhaust conductor, and a steam pipe connecting the boiler with said annular member, substantially as set forth. 115

In testimony whereof I have signed my name to this specification.

JOHN P. RYDER.
